(57) **CLAIM**

The ornamental design for a multiple blade adjustable knife, as shown and described.

DESCRIPTION

FIG. 1 is a perspective view of a multiple blade adjustable knife showing my design;

FIG. 2 is a first side view thereof;

FIG. 3 is a second side view thereof, opposite that shown in FIG. 2;

FIG. 4 is a top view thereof;

FIG. 5 is a bottom view thereof;

FIG. 6 is a front view thereof;

FIG. 7 is a back view thereof; and,

FIG. 8 is an environmental view illustrating an expanded view of the multiple blade adjustable knife of FIG. 1 positioned in hand of a subject.

The broken lines in the drawings illustrate portions of the multiple blade adjustable knife that form no part of the presently claimed design.

It will be understood that any combination of one or more unclaimed features of the design may be claimed at a later date (such as in one or more divisional or continuation applications). This specification discloses and supports the claims of any unclaimed features either alone or in combination with other unclaimed and/or claimed features.
